TRANSFER MECHANISM FOR FLAT
KNITTING MACHINES

William F. Stabert, Philadelphia, Pa., assignor to
Fashionlox, Incorporated, Dover, Del., a cor-
poration of Delaware

Application June 4, 1931, Serial No. 542,127

6 Claims. (Cl. 66—89)

This invention relates to full-fashioned knitting machines and has particular reference to a novel transfer mechanism therefor such as will enable the fabric to be fashioned in a manner different from that now in general practice.

Broadly stated, it is the principal purpose of the present invention to provide an attachment for flat knitting machines which will enable the production of transfers at different distances from the edges of a fabric being knit, such operation resulting in two or more sets of fashioning marks relative to the edges of the fabric.

In carrying out my broad inventive concept of producing several fashionings relative to the edges of a fabric, it is my further purpose to provide selective mechanism such as will automatically operate to bring the transfer points of the machine into proper position for the different fashioning operations.

It is another object of this invention to provide a mechanism which will operate selectively to vary the number of transfer points utilized in effecting the various successive transfers in a fabric being knit according to my broad inventive concept.

In its practical application to a full-fashioned knitting machine, my invention may be utilized to produce various and novel effects relative to the fashioning of a fabric. One example of a fabric which may be produced involves two fashioned areas extending side by side adjacent the edges of the fabric, the stitches in the respective fashioned areas involving a transfer over different numbers of needles. In producing a fabric such as just described, the practical embodiment of my invention may involve the utilization of single sets of transfer points of the usual type, said transfer points being adjusted according to the present invention so that one transfer will be effected by only a portion of the sets of transfer points and the second transfer by the manipulation of the complete group of transfer points, the result being the production of one fashioned area transferred over one needle and a second area transferred over two needles.

In fashioning according to my proposed practice, it is necessary that the actuation and control of certain portions of a knitting machine, which operate in coordination with transfer mechanism in known practice, be modified so as to function properly in its new association. It is, therefore, a still further object of my invention to provide an alteration and modification of such parts as is necessary to enable their coordina-

tive action when the transfer mechanism is manipulated as herein proposed.

According to general present practice, single sets of transfer points are actuated to effect a transfer of groups of stitches in successively knit courses to produce a desired shaping of the fabric being knit. Usually, although not necessarily, such stitch transfers are effected adjacent the edge of the fabric. According to my practice it is proposed to effect several transfers relative to the edge of a fabric. It will be understood that to obtain such result, it will be necessary that the transfer mechanism operate at least twice over varying areas, instead of once over corresponding areas as is the general practice, the transfer points being adjusted between successive operations so that the different fashionings may be effected at the desired points relative to the edge of a fabric and be made over the desired number of needles. As has been herein above suggested, the several transfers may produce two adjacent fashioned areas in which the stitches have been manipulated by a different number of needles; thus, for example, one area may involve a transfer of stitches over a single needle and the second area over two needles.

In fashioning by an operation involving several transfers and, more particularly, where the same are to be made in the same courses, it will be appreciated that the coordinative timing and actuation of the knitting needles and yarn carriers with the operation of the transfer points must be maintained. As will be hereinafter described in detail, I propose to modify the pattern chain which controls the operation of all of these parts of the machine so that knitting will be commenced after the transfer mechanism has operated twice instead of once, and to regulate the stops for the yarn guides so that their traverse will be coextensive with the width of the fabric as determined by the successive transfers as various courses of the fabric are knit.

To make clear the nature of my invention, I have in the following description and accompanying drawings illustrated one embodiment thereof as applied to a flat knitting machine of the Theodor Lieberknecht type. It will be understood that by reason of the differences in detail between various types of knitting machines that the specific construction of the present invention will vary with the particular machine with which it is to be utilized. The present description, however, it is believed, will suffice to make clear the essential features of my invention so as to enable one skilled in the art to

reproduce the same in a specific form as required for a particular machine. It will, therefore, be understood that I do not intend to limit myself to all of the details of construction hereinafter shown and described but, on the other hand, intend to limit myself only to the extent required by the appended claims forming a part of this specification.

In the drawings:

10 Fig. 1 is a view in front elevation of a portion of a full-fashioned flat knitting machine of the Theodor Lieberknecht type with my invention applied thereto; this disclosure includes the pattern control mechanism as modified in accordance with my invention, which is indicated out of its proper position relative to the length of the machine so as to make clear its cooperative relation with the present invention;

20 Fig. 1a is a fragmentary plan view of a section of the pattern chain according to my invention;

25 Fig. 1b is an elevation of a special cam utilized to control the transfer mechanism of the machine so as to produce transfers alternately over varying areas relative to the edges of a fabric being knit;

30 Fig. 2 is a plan view of the transfer mechanism of the machine according to the present invention, the same corresponding to the disclosure in Fig. 1;

35 Fig. 2a is a fragmentary elevation taken along the line 2a—2a of Figs. 1 and 2;

Fig. 3 is a vertical section on line 3—3 of Fig. 1;

40 Fig. 4 is a rear elevation of the portion of the machine shown in Fig. 1;

45 Fig. 5 is a plan view partly in section and with certain portions broken away looking down from about the line 5—5 of Fig. 3;

50 Fig. 6 is a perspective in fragmentary rear elevation partly in section showing a portion of the control mechanism for the transfer point carriers;

55 Figs. 7 to 15, inclusive, are detailed explanatory views showing in succession one manner of causing single sets of transfer points to produce two fashioned areas involving a different stitch transfer wherein a portion of the sets of needles are utilized for effecting one transfer and the complete set utilized for a second transfer; and
50 Fig. 16 is an enlarged diagrammatic view of a portion of a fabric produced by successive transfers relative to the edge thereof under the manipulation of single sets of transfer points operating as illustrated in Figs. 8 to 15.

60 Inasmuch as it is now the general practice to utilize single sets of transfer points to effect fashioning of a flat-knit fabric, I have selected a knitting machine employing that type of transfer mechanism with which to illustrate my invention. It will be appreciated, however, that the idea of producing several fashioned areas inwardly of the edges of a fabric may be carried out by the use of plural sets of transfer points. It will further be understood that my invention is equally useful with such mechanism to actuate the same into proper positions for the several fashioning operations in accordance with the locations in which it is desired that the respective fashionings come relative to the edge of the fabric.

65 70 75 Also, various known auxiliary devices such as shields, knives, or presser plates may be employed in cooperative relation with the transfer points or knitting needles to selectively regulate and vary the number and position of the knitted loops of the fabric which will be subjected to

manipulation when the transfer points come into operation. It will be understood that whereas such devices are ordinarily unnecessary when using single sets of transfer points regulated to operate selectively, as hereinafter described in detail, they may be employed; further, in any case where they are employed, the actuating mechanism contemplated by the present invention may be used to control the same in determining the location and number of fabric loops which will be acted upon by a transfer mechanism.

70 75 Referring now to the drawings, and in particular to Figs. 1, 2 and 3, the reference numeral 20 indicates the main frame of a flat knitting machine; 21, the front beam; 22, the back beam; 23, the center bed; 24, the main cam shaft; and 25, the knitting needle bed. Such a machine is commonly formed with a plurality of knitting sections, each of which is provided with the requisite number of yarn guides, 30, the latter being mounted on longitudinally movable yarn carrier rods, such as 31, and their extent of movement controlled by rod-contacting stops adjustably controlled by a feed shaft 32 having right and left hand portions upon which are mounted stops to adjustably determine the length of travel of the yarn carriers in both directions. The positioning of the stops is controlled through rotation of the shaft by ratchet 33 controlled by pawl 37, actuatable from the main cam shaft 24 through suitable links and levers including 35 and 36, according to well known practice.

80 85 To fashion the fabric being knit by the machine, right and left hand sets of transfer points 40a and 40b are provided to cooperate with the needles of the needle bed 25 and transfer groups of stitches of the fabric laterally one or more needles. Such sets of transfer points are mounted, respectively, on longitudinally movable carrier rods 41a and 41b, the position of these being determined by stop blocks 42a and 42b slideable on a fixed guide shaft 43 and actuatable to or from each other longitudinally of the machine by blocks 44a and 44b mounted on a right and left threaded rotatable feed shaft 45. The rotation of the shaft 45 is determined by ratchet 46 mounted thereon and controlled by a pawl 47 actuatable from the main cam shaft 24 through the lever 36.

90 95 The mechanism so far described is well known in the art. I will now proceed with a description of attachments to and modification of the transfer mechanism, above described, and the altered construction in certain other parts of the machine, which operate in coordination therewith, forming the subject-matter of the present invention.

100 While by actuation of stop blocks by rotation of the feed screw the position of the sets of transfer points may be gradually changed longitudinally of the needle bed, such arrangement in known practice is not calculated to effect any material shift in position of the transfer points except under repeated actuation which involves considerable time delay and interferes with the normal speed of production of the machine as a whole. Hence, to produce a true repositioning of the transfer points between several fashioning operations of the same such as will shift the points and selectively determine the number of the same that will be brought into operative engagement with the needle bed, I provide novel auxiliary mechanism, automatically controlled by the pattern chain and actuatable from the

main cam shaft. Such mechanism does not interfere with the gradual racking in or out of the transfer points through the controlling feed screw as the width of the fabric changes due to the fashioning operations, but, on the other hand, cooperates with the latter and enables transfer in several areas relative to the edges of the fabric. My attachment is inoperative on one transfer which takes place from the positions of the sets of transfer points determined by the controlling feed screw in the usual manner. But when the other transfer is to be made, my device bodily shifts the sets of transfer points to new positions longitudinally of the needle bed at which the second fashioning is to be effected. After such transfer, the sets of points are allowed to shift back to positions determined by the stop blocks controlled by the feed screw in accordance with the change in width of the fabric preparatory to operation in the next course in which fashioning is to be effected. I will now proceed with a detailed description of such arrangement, which, it will be apparent, permits two fashionings in selected areas relative to the edge of a fabric to be produced even on knitting machines employing single sets of transfer points. Like advantages will be attained in machines where plural sets of transfer points, presser bars, or needle shields are employed to determine the loops of the fabric on the knitting needles which will be transferred.

Referring particularly to Fig. 6, and considering therewith Figs. 1 and 4, a lever 59b operated by means hereafter to be described and connecting with the carrier rod 41b is provided to shift such rod and the transfer points 49b mounted thereon bodily longitudinally of the machine. To limit the amount of shift novel, adjustable, oppositely disposed stop buttons 51b and 52b are provided to coat with the usual stop block 42b which is actuatable from the usual feed shaft 45. Such stop buttons may be conveniently mounted on the arms of a U-shaped support 53b secured to the carrier rod 41b. To absorb shock and prevent strain on the moving parts, the actuating lever 59b may be operatively connected to the carrier rod 41b through an arm 54b, pivotally connecting therewith and having a portion positioned between sections of a spring 55b extending between the arms of the U-shaped stop button support 53b.

The actuating mechanism for the transfer point shifting lever 59b will now be described. As best shown in Fig. 6, the lever is rigidly secured to a rotatable shaft 60b actuatable by a lever 61b.

By reason of the fact that with the particular type of full-fashioned knitting machine with which my invention is illustrated, various of the carriages shift bodily during certain operations, and due to the further fact that the transfer points are gradually racked in or out by the feed screw controlled stop blocks, it is necessary to mount the actuating mechanism so as not to interfere with such movements. Accordingly, the shaft 63b is supported at one end by a block 62b hingedly secured to the block 44b on the shaft 45, and at the other end passes through a block 63b freely supported for longitudinal movement on a shaft 64.

The lever 61b which controls the shaft 60b is actuated by a vertically reciprocal bar 65 which is provided with a block 66b, mounted for free longitudinal movement, which connects with the lever 61b through a pin 67b.

It will be understood that while I have described the actuating parts controlling the transfer point carrier 46b, like parts 50a, 51a, 52a, 53a, 54a, 55a, 60a, 61a, 62a, 63a, 66a, and 67a, are provided for the other transfer point carrier 40a.

Referring now to Fig. 4, actuating bars such as 70 and 72 are rigidly secured to the bar 65 through blocks 71 and 73. Two of such bars are desirable for the purpose of rigidity and strength, and these are connected, as shown in Fig. 5, to arms 74 and 75 which are in turn secured to a rocking shaft 76 journaled in blocks supported by the back beam, 22, of the machine.

To actuate the rocking shaft 76 and, thence, through the mechanism above described, the transfer point carriers, a long arm 77 is rotatably mounted on a shaft 78, which may be the catch bar shaft of the machine, and is provided with a stub shaft 85 supporting a truck or roller 80, intended to coat with a special cam 81 on the main cam shaft 24, as shown in Figs. 1 and 3. The arm 77 is provided with an extension which is connected by a suitable link 78a with an arm 79b rigidly secured to the shaft 76.

The special cam 81, the shape of which is shown in Fig. 1b, is calculated to actuate the various parts above described to shift the transfer point carriers 41a and 41b longitudinally with respect to the needle bed of the machine. An arm 82 bifurcated at one end to coat with the roller 80 and shift the same on and off the cam 81 is provided, the same being conveniently pivotally supported on a bracket 83 associated with the arm 77. To effect such operation the roller 80 is freely supported on the stub shaft 85 so as to be movable axially thereto, or, if desired, the stub shaft may be supported for longitudinal movement relative to the arm 77. A spring 84 is provided to hold the arm 77 in proper position.

As is customary practice, the operation of the machine during knitting and fashioning and the change from one to the other of such operations is effected by suitable cams, not shown, on the cam shaft 24, and controlled by a pattern chain 90, shown in Fig. 1, through the usual coacting mechanism including the finger 91. By the employment of buttons 95 on the pattern chain with which the finger 91 coacts, the operation of the machine is changed from knitting to transferring. This arrangement is well understood and need not be described in detail, it being sufficient to state that while the finger 91 is held raised by the button 95, the machine operates to transfer.

The mechanism just described is not altered except that when the several transfers are to be effected in the same courses the buttons 95 on the pattern chain are double the length of those usually employed, this enabling the usual transfer cam to cause two, instead of the usual one, operations of the transfer points, as is one capability of the present invention.

During one of the transfer operations the machine operates as usual, the position of the sets of transfer points being determined by the stop blocks 42a and 42b. For the other transfer, for which the transfer points are to be reset longitudinally of the needle bed, the mechanism above described, including the levers 60a and 60b, must operate while the button 95 maintains the machine in transfer operation. Accordingly, I provide a second set of buttons 105, of usual size, on the pattern chain, in proper relation to the buttons 95, as shown in Fig. 1a. A second finger 101 is provided adjacent the finger 91, to coat with those buttons, said finger being connected 70 75

- through suitable rods and links, including 102 and 104, with a rod 103. Rod 103 extends longitudinally of the machine and, as shown in Figs. 1 and 4, engages a projection 106 on the arm 82. 5
- With such arrangement, as the finger 101 engages the button 105 on the pattern chain, the rod 103 moves longitudinally to cause the arm 82 to throw the roller 80 on the special cam 81, which actuates the lever 77 and the mechanism associated therewith to shift the transfer carriers 41a and 41b and, hence, the transfer points 40a and 40b longitudinally to an extent determined by the sets of stop buttons 51a—52a and 51b—52b in cooperation with the stop blocks 42a and 42b. 10
- The extent and direction of shift can, of course, be regulated as desired by adjustment of the stop buttons and the leverage of the mechanism together with the size of the buttons 105 on the pattern chain. 15
- When the button 105 passes the finger 101, a spring 107 returns the rod 103 to ordinary position and the roller 80 is pulled off the cam 81. 20
- As heretofore set forth, the racking in and out of the stop blocks mounted on screw threaded shafts 32 and 45 determine generally the position of the yarn carriers 30 and sets of transfer points 40a and 40b, and are controlled respectively by ratchets 33 and 46 through suitable pawls or clawkers actuatable by an arm 36 controlled in the usual manner. If it is desirable that the successive transfers of the fashioning mechanism be each over only one needle, the pawl 47 should be adjusted to be effective over only one notch of the ratchet 46 on the feed shaft 45. 25
- Since ordinarily the stops for the yarn carriers 31 are moved with the feed shaft 32 through the ratchet 33 after each transfer to realign the yarn guides 30 with the new width of the fabric resulting from a single fashioning, it is necessary, where there are two successive transfers during the fashioning operation, that suitable adjustment be made. The proper alignment of the yarn carriers may be maintained by actuating the yarn carrier stop feed shaft 32 only after every other transfer operation. 30
- This may be conveniently done by providing a pin 117 on the pawl 37 which coacts with the ratchet 33, an arm 103 to disengage the pawl from the ratchet after every second transfer operation, as shown in Figs. 2 and 2a. The arm 103 may be mounted on a shaft 109, which is in turn mounted on a bell-crank 110 so as to be vertically movable. The bell-crank is connected to the control rod 103, which shifts the transfer points on every second transfer operation, through a link 111 which connects with a collar 112 on the rod, as shown in Fig. 4. Thus, the feed shaft and, hence, the yarn carrier stops will be actuated so as to bring the yarn guides in proper position relative to the edges of the fabric when two fashionings are made. 35
- Under the usual adjustment of the stops for the transfer point carriers, and according to my main purpose, groups of stitches in successive courses occupying corresponding positions are transferred so as to constitute fashioned areas extending parallel to the edges of the fabric. If it is desirable that the successive fashionings produced by the machine operating with my mechanism should be at an angle to the edges of the fabric, as for example, in making the fashionings in the heel portions of full-fashioned hosiery, a simple mechanism may be provided to accomplish this purpose. The usual ratchet, designated by the numeral 120, on the transfer carrier feed 40
- shaft 45, operates, according to general practice, through coaction with the pawl-carrying arm 121 to give the feed shaft a reverse rotation from that produced by actuation of the ratchet 46 when the arm 121 is set in operative position. Where there are two transfer operations relative to the edges of the fabric, as herein contemplated, and it is desired that the line of fashioning marks run at an angle to the edges, such mechanism should operate only once for every other transfer. Accordingly, a star wheel 122, having two diametrically opposite pins supported on one of its faces is arranged on a convenient support 123 (see Fig. 2), and a pawl 124, mounted pivotally on the arm 121 so as to engage and rotate the wheel a quarter turn on each operation of the fashioning mechanism. The pins are so arranged that on alternate quarter revolutions of the star wheel one or the other will engage the edge of the arm 121 and prevent the pawl thereon from engaging the ratchet 120. Thus, the feed shaft will adjust the position of the transfer point stops, and, hence, the fashioning points, only after every alternate fashioning operation. 45
- When producing parallel double fashioning in the calf or heel of a stocking fabric, or in producing the usual single fashioning in such portions, the star wheel will be inoperative when the fashioning marks are to run parallel to the edge. 50 To render the star wheel inoperative, a latch 125 supported on the frame of the machine is provided to engage a pin 126 carried on the pawl arm 121, this arrangement serving to hold the pawl arm 121 out of engagement with the ratchet 120, and hence withdrawing the pawl 124 from engagement with the star wheel. 55
- In Fig. 16 I have illustrated a fabric fashioned in two areas relative to the edge, one of said areas involving a loop transfer of one needle, and the other by two needles. This may be readily produced by a machine provided with the mechanism of my invention. In Figs. 7-15 I have shown one way in which my mechanism may manipulate the transfer points to produce such a fashioned fabric. 60
- When the fashioning is to begin the fashioning points are in the position shown in Fig. 7, only a small number of the points being in operative position relative to the needle bed. Such position is determined by the stop blocks 42a and 42b in cooperation with the respective stops 52a and 52b on the transfer point carriers. The points then pick the group of fabric loops *a*, in Fig. 16, off the needles as shown in Fig. 8, shift them one needle as shown in Fig. 9, and then deposit them on the new needles as in Fig. 10. The fashioning points are then shifted to a new position by my mechanism as shown in Fig. 11, such position being determined by cooperation of the stops 51a and 51b on the carrier with the respective stop blocks 42a and 42b. The new position may, if desired and as shown, be such as to render the whole group of transfer points operable relative to the needle bed. On the second transfer, the points engage the group of fabric loops *b*, in Fig. 16, and in addition the loops in group *a*, as shown in Fig. 12. The points then shift the loops one needle, as in Fig. 13, according to cooperation of the stops 52a and 52b with the new position of blocks 42a and 42b, the latter having been racked in by means of the ratchet 46 following the first transfer. The loops are then deposited on the needles, as in Fig. 14, to produce the fashioning as illustrated. It will be understood that with the operation as shown and described, 65
- 70
- 75

the group *a* of fabric loops will be transferred two needles, by reason of successive transfers over one needle, and group *b* will be transferred over only one needle. Two fashioning marks will thus be produced relative to the edge of the fabric. Of course, by suitable adjustment of the stops 51, *a* and *b*, 52, *a* and *b*, the stop blocks 42, *a* and *b*, and the shifting mechanism, the several transfers may be made at any desired distances from the edge of the fabric, and of course may be spaced so that each group will include a transfer by only one needle. After the second fashioning, the transfer points are adjusted back, as shown in Fig. 15, to a new position relative to the edge of the fabric corresponding to that shown in Fig. 7.

For convenience in enabling a change from double to the usual single transfer relative to the edge of the fabric being knit, I provide a stop 131, as shown in Fig. 5, on the arm 77 which may be manipulated to prevent the roller 80 from engaging the special cam 84 under actuation of the roller control arm 82 by the pattern chain controlling rod 103. To this end the collar 106 on the rod (see Fig. 4) is mounted loosely and seats against a spring held against longitudinal movement relative to the shaft. When the stop 131 is in position, the collar 106 will compress the spring, the result being that the lost motion thereof will keep the arm 82 from pulling the roller on to the cam.

By my invention above described, it will be appreciated that several fashionings relative to the edges of a fabric may be readily produced. Successive fashioned areas, where adjacent, may be over a different number of needles. The positions of the several fashioned areas with respect to the edges of the fabric and each other may be varied as desired. Also, the number of transfer points employed in the several transfers are subject to variation. It will be apparent, too, that the machine may readily be adjusted by one skilled in the art to render my mechanism inoperative and permit fashioning according to known practices.

What I claim is:

1. In a flat knitting machine, a needle bed, a cam shaft, longitudinally movable transfer point carriers, means including an arm having swinging movement connecting with each of the carriers and operable between transfer operations for shifting the carriers in either direction to reposition the transfer points longitudinally of the needle bed, and means on the cam shaft for actuating said carrier shifting means alternately in opposite directions.

2. In a flat knitting machine, a needle bed, longitudinally movable transfer point carriers, means for effecting a plurality of transfer operations between knitting operations, and means including a pivoted arm connecting with each of the transfer point carriers and actuating means therefor for effecting longitudinal adjustment of the transfer point carriers between transfer operations.

3. In a flat knitting machine, a needle bed, longitudinally movable transfer point carriers, a screw-threaded spindle, stops cooperative with the carriers to cause longitudinal movement thereof, a ratchet on the spindle, pattern chain controlled means cooperative with the ratchet for adjusting the stops a distance of at least one needle on each transfer operation, a second ratchet on the spindle, and means cooperative with the second ratchet on alternate transfer operations to adjust the stops a distance of at least one needle in the opposite direction, whereby the loop transferred areas in a fabric being knit will be angularly related to the edge of the fabric.

4. In a flat knitting machine, a needle bed, longitudinally movable transfer point carriers, means for positioning the carriers longitudinally of the needle bed means for shifting the carriers to reposition the transfer points longitudinally of the needle bed, stops for limiting the shifts of the carriers, and lost-motion connections between the shifting means and the carriers to prevent strain on the actuating means when the carriers contact with the stops.

5. In a flat knitting machine, a needle bed, longitudinal transfer point carriers, means for positioning the carriers longitudinally of the needle bed means for shifting the carriers to reposition the transfer points longitudinally of the needle bed, and a shock-absorbing connection between said carriers and said shifting means, said connection comprising a resilient element secured to one of said members and means secured to the other of said members connected with said resilient element.

6. In a flat knitting machine, a needle bed, a longitudinal movable transfer point carrier, means for positioning the carriers longitudinally of the needle bed means for shifting the carrier to reposition the transfer points longitudinally of the needle bed, a U-shaped bracket secured to the transfer point carrier supporting opposing springs between the arms thereof, and an arm connecting the carrier to the shifting means disposed between said opposing springs.

WILLIAM F. STABERT. 55
